(57) **CLAIM**

The ornamental design for a surgical instrument, as shown and described.

DESCRIPTION

FIG. 1 is a perspective, bottom right side view of a surgical instrument showing our new design.

FIG. 2 is a top view of our new design shown in FIG. 1.

FIG. 3 is a bottom view of our new design shown in FIG. 1.

FIG. 4 is a front view of our new design shown in FIG. 1.

FIG. 5 is a rear view of our new design shown in FIG. 1.

FIG. 6 is a right-side view of our new design shown in FIG. 1; and,

FIG. 7 is a left-side view of our new design shown in FIG. 1.

The broken lines consisting of short broken lines show the remaining portions of the surgical instrument that form no part of the claimed design.

1 Claim, 7 Drawing Sheets
